[57] CLAIM

We claim the ornamental design for a bezel for a computer, as shown and described.

DESCRIPTION

FIG. 1 is an upper right front perspective view of a bezel for a computer, with the rest of the unclaimed portion of a computer shown in phantom lines for illustrative purposes only and forms no part of the claimed design;

FIG. 2 is a front elevational view thereof, the rear contains no design features;

FIG. 3 is a left side elevational view thereof;

FIG. 4 is a right side elevational view thereof;

FIG. 5 is a top plan view thereof; and,

FIG. 6 is a bottom plan view thereof.
